UNITED STATES PATENT OFFICE.

JOHN F. CARD, OF THREE RIVERS, MICHIGAN, ASSIGNOR TO THE SHEFFIELD CAR COMPANY,
OF THREE RIVERS, MICHIGAN.

ARMATURE-CORE.

No. 891,906.

Specification of Letters Patent.

Patented June 30, 1908.

Application filed March 16, 1907. Serial No. 362,690.

To all whom it may concern:

Be it known that I, JOHN F. CARD, a citizen of the United States, residing at the village of Three Rivers, county of St. Joseph, 5 State of Michigan, have invented certain new and useful Improvements in Armature-Cores, of which the following is a specification.

This invention relates to improvements in armature cores for dynamo electric machines. 10 The main objects of this invention are, first, to provide an improved armature core for dynamo electric machines, which is "ventilated", or so constructed as to prevent its becoming unduly heated in use. Second, to 15 provide an improved armature core having these advantages in which the parts are very simple and economical to produce and easily assembled.

Further objects, and objects relating to details of construction, will definitely appear 20 from the detailed description to follow.

I accomplish the objects of my invention by the devices and means described in the following specification.

25 The invention is clearly defined and pointed out in the claims.

A structure embodying the features of my invention is clearly illustrated in the accompanying drawing, forming a part of this 30 specification, in which,

Figure 1 is a central longitudinal section through a structure embodying the features of my invention taken on a line corresponding to line 1—1 of Fig. 2, the shaft 1 being 35 shown in full lines. Fig. 2 is a transverse section taken on a line corresponding to line 2—2 of Fig. 1. Fig. 3 is a perspective view of one of the spacing members 6. Fig. 4 is a detail of one of the spacing rings 5.

40 In the drawing, the sectional views are taken looking in the direction of the little arrows at the ends of the section lines, and similar reference numerals refer to similar parts throughout the several views.

45 Referring to the drawing, 1 represents the shaft of the armature. The core is made up of a plurality of metal laminae or plates 2, having radial projections 3 adapted to form channels for the armature coils. (Not 50 shown). The plates are also provided with a plurality of registering openings 4. The plates are secured to the shaft to hold them in proper place preferably by the key 8. The plates are preferably arranged on the shaft in 55 groups, the groups being spaced by the rings

5, having a plurality of perforations 7 therein. A pair of rings is preferably located between each group, particularly on large sized cores. It is obvious that the number of spacing rings could be varied according to the requirements. 60

The staple-like spacing members 6 are of the same width as the spacing rings, and are arranged between the projections of the groups of plates, as clearly appears in Fig. 2. 65 The number of these spacing members arranged between each group, it is obvious, may be considerably varied. The means for clamping the plates upon the shaft are not here illustrated as they form no part of this 70 present invention, and are well understood in the art.

The openings 4 are preferably arranged through the plates in groups, those of the inner group being embraced by the inner ring and those of the outer group being embraced by the outer ring. The openings in the two 75 groups are preferably arranged in a zigzag relation as this renders the ventilation somewhat more effective.

By thus arranging the parts, the core is formed so that it is open for circulation so that its undue heating in use is prevented. The parts are very economical to produce and may be readily assembled. 80

Having thus described my invention, what I claim as new and desire to secure by Letters Patent is:

1. In an armature core, the combination with a shaft, of a plurality of plates keyed to 90 said shaft, said plates having a plurality of registering openings therethrough arranged in series and radial projections forming channels to receive the armature coils; perforated spacing rings arranged in pairs to divide said 95 plates into groups; the inner spacing ring being arranged between the inner and outer series of said openings in said plates; and staple-like spacing members arranged between said projections on said plates. 100

2. In an armature core, the combination with a shaft, of a plurality of plates keyed to 105 said shaft, said plates having a plurality of registering openings therethrough and radial projections forming channels to receive the armature coils; perforated spacing rings arranged to divide said plates into groups; and staple-like spacing members arranged between said projections on said plates.

3. In an armature core, the combination 110

- with a shaft, of a plurality of plates keyed to said shaft, said plates having a plurality of registering openings therethrough and radial projections forming channels to receive the 5 armature coils; and perforated spacing rings arranged in pairs to divide said plates into groups the inner spacing ring being arranged between the inner and outer series of said openings in said plates.
- 10 4. In an armature core, the combination with a shaft, of a plurality of plates keyed to said shaft, said plates having a plurality of registering openings therethrough and radial projections forming channels to receive the 15 armature coils; and perforated spacing rings arranged to divide said plates into groups.
5. An armature core, comprising a plurality of plates, having registering openings therethrough and provided with radial pro-

jections forming channels to receive the 20 armature coils; perforated rings arranged between said plates; and staple-like spacing members arranged between said projections on said plates.

6. An armature core, comprising a plurality of plates, having registering openings therethrough and provided with radial projections forming channels to receive the armature coils; and perforated rings arranged 25 between said plates.

In witness whereof, I have hereunto set my hand and seal in the presence of two witnesses.

JOHN F. CARD. [L. s.]
